(57) **CLAIM**

The ornamental design for a stool, as shown and described.

DESCRIPTION

FIG. 1 is a front, top perspective view of a stool, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 1;

FIG. 11 is an enlarged view of detail "11" identified in FIG. 2;

FIG. 12 is an enlarged view of detail "12" identified in FIG. 6;

FIG. 13 is an enlarged view of detail "13" identified in FIG. 6;

FIG. 14 is an enlarged view of detail "14" identified in FIG. 8; and,

FIG. 15 is an enlarged view of detail "15" identified in FIG. 8.

The dash-dash broken lines in the figures illustrate the portions of the stool that form no part of the claimed design. The dot-dash broken lines in FIGS. 1, 2, 6, and 8-15 depict the borders of the enlarged detailed views and form no part of the claimed design.

1 Claim, 15 Drawing Sheets
